UNITED STATES PATENT OFFICE.

LEBBEUS A. KOPLIN, OF AKRON, OHIO.

REIN-HOLDER.

SPECIFICATION forming part of Letters Patent No. 293,476, dated February 12, 1881.

Application filed August 9, 1883. (No model.)

To all whom it may concern:

Be it known that I, LEBBEUS A. KOPLIN, a citizen of the United States, residing at Akron, in the county of Summit and State of Ohio, 5 have invented new and useful Improvements in Rein-Holders, of which the following is a specification.

The object of my invention is to provide a simple and effective device for holding the 10 reins of a harness when the driver alights, which may be easily and quickly operated and automatically locked to prevent the escape of the reins.

To this end my invention consists in a pair 15 of holding-jaws clamped to the splash-board and actuated by a cam-lever, a yielding elastic plate being arranged above the lower or stationary jaw, with a spring to raise the upper or pivoted jaw, when the reins are removed, whereby the device may be used with 20 reins of different thicknesses, and be quickly and easily operated.

Referring to the drawings forming part of 25 this specification, Figure 1 is a side elevation. Fig. 2 is a side elevation, with the parts below the pivoted jaw in section. Fig. 3 is an end elevation.

A A in said drawings represent clamps, which are secured to lugs *a* upon the under 30 side of a plate or jaw, B, by means of bolts *b*, passing through said lugs and having nuts *b'* upon one end. These clamps are for the purpose of securing the rein-holder to the splash-board, the latter being introduced between them, and the nuts *b'* turned up until the edge 35 of the dash is firmly grasped between them, as shown in Fig. 1. Near one end of the plate B, and upon each side thereof, are formed rearwardly-projecting lugs C, between which 40 the upper jaw, D, of the holder is pivoted. In front of the lugs C, and forming part of the said plate, rise arms E, their ends projecting above the upper surface of the jaw D, and between the extremities of said arms is pivoted a lever, F, having a cam, *f*, which rests upon the jaw D. This cam is so formed that 45 when the lever is thrown up into the position shown in Fig. 1 the jaw D is allowed to rise, and when thrown down, as in Fig. 2, it forces 50 the jaw down until the cam lies in the vertical plane of its pivotal point, or so nearly that the upward pressure upon the jaw will not retract the lever. A spring, G, is set between the plate B and the pivoted jaw D, by which

the latter is normally raised to the position 55 shown in Fig. 1.

H represents an elastic plate, which over-lies the plate B, and which is held by its own tension somewhat above the lower plate. The leaf H is set in notches in the arms E, and may 60 be held in place by any suitable means—as, for example, by a pin, *e*.

The operation of this device is as follows: Being attached to the splash-board in the manner described, with the opening of the jaws 65 toward the rein-hand, the reins are laid upon the spring-plate H, and the lever F is thrown down, depressing the pivoted jaw and clamping the reins tightly between it and the spring-plate, the yield of the latter compensating for 70 the varying thickness of different reins. The cam *f*, when the lever is thrown down, lies so nearly in the line of the pivotal point of the lever F that the pressure between the jaws 75 cannot unlock the cam and throw up the lever, releasing the reins.

Instead of using two pairs of clamps A, a single pair only may be used, having suitable width.

What I claim is—

1. A rein-holder consisting of a pair of clamping-jaws, whereof one is movable and actuated by a cam-lever which locks said jaw down, substantially as described.

2. The combination, with the lower jaw of 85 a rein-holder, of a spring-plate overlying the same, whereby reins of varying thickness may be clamped between the jaws, substantially as described.

3. The combination, with the lower jaw, B, 90 having the spring-plate H, of the pivoted jaw D and the cam-lever F, substantially as described.

4. The combination, with the jaw B and pivoted jaw D, of the spring G and cam-lever F, 95 substantially as described.

5. The rein-holder described, consisting of the clamps A A, the jaw B, having spring-plate H, the pivoted jaw D, spring G, and cam-lever F, pivoted to arms E, substantially 100 as described.

In testimony whereof I have hereunto set my hand in the presence of two subscribing witnesses.

LEBBEUS A. KOPLIN.
